UNITED STATES PATENT OFFICE.

WILLIAM GRAHAM AND WILLIAM H. STALEY, OF LONDON, OHIO.

POST-HOLE-BORING MACHINE.

SPECIFICATION forming part of Letters Patent No. 269,410, dated December 19, 1882.

Application filed April 5, 1882. (No model.)

To all whom it may concern:

Be it known that we, WILLIAM GRAHAM and WILLIAM H. STALEY, of London, in the county of Madison and State of Ohio, have 5 invented a new and Improved Post-Hole-Boring Machine, of which the following is a full, clear, and exact description.

Our invention relates to improvements in machines for boring post-holes; and it consists 10 in the peculiar construction and arrangement of parts, as hereinafter fully described.

Reference is to be had to the accompanying drawings, forming part of this specification, in which similar letters of reference indicate corresponding parts in all the figures.

Figure 1 is partly a side elevation and partly a sectional elevation. Fig. 2 is a plan view. Fig. 3 is a detail of the borers. Fig. 4 is a detail of the adjustable driving-gear.

20 A represents the posts, and B the cross-bars, of a supporting-frame to stand upon the ground between the places where the post-holes C are to be bored.

E represents a horizontal frame of four timbers, in which the boring-shafts F are mounted by a revolving sleeve, G, and sliding blocks H, the said blocks being fitted in grooves I, to slide along the timbers for setting the borers the required distance apart, and also provided

30 with stops J K to hold them in position. The sleeves G have a bevel-wheel, M, for being rotated to turn the borers, with which borers said sleeves connect by a pawl, N, on the sleeves, and a groove, O, in the borer-shaft F.

The wheels M are geared with the master-wheel P by wheels Q, shafts R, and pinions S. The shafts R are fitted in pinions S, and also in bearings T, secured to the lower cross-bar B, so that the shafts R will slide along with

40 blocks H, carrying the borers. The shafts R, being square to connect properly with pinions S for transmitting the motion, have a thimble, U, in bearings T, revolving with them, and giving the support to the shafts in said bearings.

45 The boring-shafts F have a lever, W, connected at the upper end by a swivel, X, by which to raise them out of the ground when required, and the levers have a swiveled fulcrum, Y, allowing them to swing as the borers

are shifted along the frame E, and also contrived to shift the levers along said fulcrums to accommodate the shifting borers. The master-wheel P is located in the frame A B, and gears on its opposite sides with the pinions S of the respective borers, so that the back-thrusts of the gearing of the respective borers are balanced one by the other. The said master-wheel P is provided with a sweep, Z, on its shaft A', to which a horse is to be hitched for applying the power.

The machine is designed for boring holes, say six, seven, and eight feet apart, according to the length of the boards to be used; but it may of course be constructed to be adjusted for any distances within practical limits. The machine here shown is designed to bore six feet apart when the two borers are set in the inner positions, eight feet when both are set out, and seven feet when one is out and one in.

7c The pawls N are constructed to spring into the grooves O of the borers, and they are provided with a lever, a, said pawls and levers being mounted on the sleeve G and wheel M, suitably for connecting them and the borers when the borers are to be worked, and for disconnecting them when not required to work, it being sometimes necessary to work one borer and not the other. The levers a will be fastened by pins b in wheels M, to hold pawls N 80 out of gear with the borer-shafts; or any other suitable device may be employed to connect and disconnect the borers. In practice the frame will be mounted on wheels for being moved about conveniently.

Having thus fully described our invention, we claim as new and desire to secure by Letters Patent—

1. The combination, with the grooved boring-shafts F, of the rotary sleeves G, connected by the pawls N with said shafts, and the slide-blocks H, having stops J K, as and for the purpose specified.

2. The combination of boring-shaft F, sleeve G, wheel M, and pawl N, said boring-shaft 95 having a groove for said pawl, substantially as described.

3. The combination, with boring-shaft F and

sleeve G, of the lever W, swiveled to said shaft and being adjustable on its fulcrum, together with the said boring-shaft, arranged adjustably along the frame, substantially as specified.

5

4. The combination of driving-wheel P, pinion S, sliding shaft R, thimble U, bearing T,

wheels Q and M, and the adjustable boring-shaft F, substantially as specified.

WILLIAM GRAHAM.

WILLIAM H. STALEY.
